WITNESS:

Robert H. Fraser
INVENTOR
BY *Victor J. Evans*
ATTORNEY

UNITED STATES PATENT OFFICE.

ROBERT H. FRASER, OF BATTLE CREEK, MICHIGAN.

RECORD BINDER.

Application filed June 7, 1921. Serial No. 475,757.

To all whom it may concern:

Be it known that I, ROBERT H. FRASER, a citizen of Canada, residing at Battle Creek, in the county of Calhoun and State of Michigan, have invented new and useful Improvements in Record Binders, of which the following is a specification.

This invention relates to a holder for phonographic records of the disc type, the 10 general object of the invention being to provide means whereby the envelope in which the record is sold can be utilized as a part of the holder.

Another object of the invention is to provide means whereby new records may be 15 easily and quickly placed in the holder or old records removed therefrom.

This invention also consists in certain other 20 features of construction and in the combination and arrangement of the several parts, to be hereinafter fully described, illustrated in the accompanying drawings and specifically pointed out in the appended claims.

In describing the invention in detail, reference will be had to the accompanying 25 drawings wherein like characters denote like or corresponding parts throughout the several views, and in which:—

Figure 1 is a view showing an envelope 30 with the record therein and with holes punched therein for permitting the envelope to be placed in my holder.

Figure 2 is a view of the base plate.

Figures 3 and 4 are views of two different 35 forms of spacer plates.

Figure 5 is a sectional view through a holder, the section being taken on the line 3—3 of Figure 2.

As shown in these views I retain the envelopes 1 in which the disc records 2 are 40 sold and I bind these envelopes together at the corners so that they can be turned like the leaves of a book. I provide a base plate 3 upon which the records are to be placed. I 45 punch a pair of holes 4 in one corner of the plate and I form similar holes 5 in one corner of each envelope, these holes being arranged so that they lie in a plane adjacent a line tangent to the circumference of the rec-

ord. Spacer plates 6 are placed between the envelopes, these plates having holes 7 therein which register with the holes in the envelopes and those in the base plate. The envelopes are placed one upon another with their holes registering with each other and with the holes in the base plate and with the holes in the spacers. A lacing 8 is then passed through the holes, as shown in Figure 5, and its ends suitably secured together so that the envelopes are fastened together like the leaves of a book. This will permit the envelopes to be turned over to permit access to those underneath so that the records can be removed or replaced from these envelopes. I may form one of the spacers of triangular shape, as shown at 6' in Figure 4, so that an index of the contents of the book or holder 55 can be placed thereon. This plate should be placed at the top. If desired eyelets may be placed in the holders 5 to prevent the lacing 60 from tearing the envelopes. 65

If desired a rubber band can be placed around the holder adjacent the open ends of the envelopes to keep the records from dropping out.

It is thought from the foregoing description that the advantages and novel features 70 of my invention will be readily apparent.

I desire it to be understood that I may 75 make changes in the construction and in the combination and arrangement of the several parts, provided that such changes fall within the scope of the appended claim.

What I claim is:—

A holder for phonographic records comprising a base, a number of record-receiving envelopes, said envelopes and base having registering openings, said openings being arranged at one corner of each envelope, a lacing passing through the opening for hingedly connecting the parts together and spacer plates having openings therein registering with the openings in the envelopes, one of said spacer plates being arranged to receive an index.

In testimony whereof I affix my signature. 95

ROBERT H. FRASER.
